UNITED STATES PATENT OFFICE.

ROBERT L. CLAUSE, OF SEWICKLEY, PENNSYLVANIA, ASSIGNOR TO PITTSBURGH PLATE GLASS COMPANY, A CORPORATION OF PENNSYLVANIA.

APPARATUS FOR MAKING SHEET GLASS.

Application filed May 13, 1925. Serial No. 29,932.

To all whom it may concern:

Be it known that I, ROBERT L. CLAUSE, a citizen of the United States, and a resident of Sewickley, in the county of Allegheny and State of Pennsylvania, have made a new and useful invention in Improvements in an Apparatus for Making Sheet Glass, of which the following is a specification.

The invention relates to apparatus for making glass in a continuous sheet or ribbon by a rolling process. It has for its primary object the provision of improved means for supporting the glass while it hardens or sets following its formation between the rolls, and for forwarding it during such period in such manner as to avoid any substantial stretching. Certain embodiments of the invention are illustrated in the accompanying drawings wherein:

Figure 1 is a vertical section through one form of the apparatus as applied to a glass tank. And Fig. 2 is a vertical section illustrating a modification.

Referring to Fig. 1, the numeral 1 indicates a melting tank, preferably of the regenerator type having at its forward end an outlet slot 2. This outlet slot is carried in a vertical movable clay member 3 constituting the front wall of the furnace 25 and supported for vertical adjustment and for removal in the metal frame 4 suspended by means of the chains 5 from a suitable crane above. The frame 4 is also supported adjustably from beneath by means of the jack 6. Provision is made 30 for cutting off the flow of glass to the outlet slot by the use of the refractory gate 7 and the water cooled, gate 8 supported from above for vertical movement by means 35 of suitable tackle, including the chains 9 and 10. At the front of the furnace is a car or truck 11 mounted upon the track 12 for transverse movement and carrying the frame 13 in which are journaled the 40 sizing rolls 14 and 15 suitably driven by means which are not shown and provided with passages to permit of the circulation of a cooling fluid, such as water, through the rolls. The frame 13 which carries the 45 rolls may be adjusted toward and from the furnace by means of screws 16 swiveled in the body of the truck 11 and rotated in suitable nuts carried by the framing, this rotation being accomplished by means of 50 the worm wheels 17 carried by the screw 55

shafts and operated by worms 18 on the transverse shaft 19. This shaft 19 is rotated by means of a handle 20.

Immediately in advance of the rolls is an apron 21 supported at one end by the frame 60 13 and carried at the other end upon a pivot rod 22 journaled in the end of the casting 23. The apron 21 carries the series 65 of rolls 24 to 30, which are hollow and cooled by a circulation of fluid, preferably water. The rolls 26, 27, 28 and 29 are driven by the sprocket chain 31 passing over sprockets secured to the ends of the roll shafts and round the drive sprocket 32, and the rolls 24 and 25 are driven from 70 the roll 26 by means of the sprocket chains 33 and 34 passing around suitable sprockets on the ends of the roll shafts. Forward of the apron 21 is the leer 35 provided with the rolls 36 driven by the chain 37 passing 75 over sprockets carried by the ends of the roll shafts. A refractory cover 37^a is preferably provided above the apron and the space between the cover and apron is heated 80 by means of the gas burners 38, the vertically movable damper 39 also serving to regulate the temperature in this space and in the entrance portion of the leer.

The table of which the rolls 24 to 30 constitute a part is also provided with a 85 plurality of platens 40 to 44, arranged as illustrated, and made hollow so that a cooling fluid such as water may be circulated therethrough. These platens preferably fit around the rolls as indicated in order to 90 provide a table surface which is approximately continuous, the surface of such table being made up in part of the flat upper faces of the platens and in part by the upper peripheries of the rolls. This bed or table 95 construction prevents any sagging of the glass sheet 45 as it passes thereover, and by the time the glass reaches the roll 28, its lower surface is so chilled by contact with the cooled rolls and platens that it will 100 support the sheet against any substantial sagging even though the central and upper portions of the sheet are relatively soft.

The provision of a bed of this kind permits of the formation of a sheet which is 105 relatively soft after it passes the rolls 14 and 15, so that a greater speed in the generation of the sheet is permissible, and any seed or bubbles which are flattened as the glass passes between the rolls have an opportunity 110

to resume their spherical shape (because of the softness of the glass) after the glass passes the rolls. The provision of the rolls interspersed between the platens is also an advantage as there is less tendency to stretch the glass than would be the case if a continuous platen were used and sufficient traction were applied at the front end of the platen by the leer rolls to drag the glass over the platen. It is desirable to avoid this stretching, as this tends to make the glass of non-uniform thickness and also tends to elongate seed and bubbles so that they have greater visibility in the glass than if left in spherical shape.

Fig. 2 illustrates another construction in which the upper surface of the table carried by the apron 46 is in the same horizontal plane as the pass between the rolls 47 and 48. The bed, in this case, comprises the cooling rolls 49 to 54 and the interspersed platens 55 to 58, such platens being in this instance preferably made of triangular cross section and being cooled by the circulation of fluid therethrough, as in the other type of construction. A cover 59 is provided above the glass as in the other type of construction, and the space therebeneath is heated by means of the burners 60. In this construction, the chilling effect of the roll 48 upon the glass is less than that of the roll 15 in the Fig. 1 construction, so that the chilled skin formed by this roll is less than in the Fig. 1 construction, but the provision of the platen 55 fitting into the space between the rolls, makes this arrangement feasible, since the glass has no opportunity to sag after it leaves the roll 48.

What I claim is:

1. Apparatus for forming sheet glass continuously in a sheet or ribbon from a body of molten glass, comprising a pair of cooled rolls contacting with said molten body of glass, and a table for receiving the glass and forwarding it, comprising a series of spaced rollers, a series of platens inter-

spersed between the rollers having their upper surfaces substantially flat and filling the spaces between the rollers, and means for cooling the rollers and platens.

50

2. Apparatus for forming sheet glass continuously in a sheet or ribbon from a body of molten glass, comprising a pair of cooled rolls contacting with said molten body of glass, and a table for receiving the glass and forwarding it, comprising a series of spaced rollers, a series of platens interspersed between the rollers having their upper surfaces substantially flat and filling the spaces between the rollers, means for driving the rollers, and means for circulating a cooling fluid through the rollers and platens.

55

3. Apparatus for forming sheet glass continuously in a sheet or ribbon from a body of molten glass, comprising a pair of cooled rolls contacting with said molten body of glass, and a table for receiving the glass and forwarding it, comprising a series of spaced rollers, a series of platens interspersed between the rollers having their upper surfaces substantially flat and filling the spaces between the rollers, forwarding means in advance of the table, and means for circulating a cooling fluid through the rollers and platens.

60

4. Apparatus for forming sheet glass continuously in a sheet or ribbon from a body of molten glass, comprising a pair of cooled rolls contacting with said molten body of glass, and a table for receiving the glass and forwarding it, comprising a series of spaced rollers, a series of platens interspersed between the rollers having their upper surfaces substantially flat and filling the spaces between the rollers, and means for cooling the rollers and platens, the said platens having their side walls concave so as to fit around the rolls.

70

In testimony whereof, I have hereunto subscribed my name this 5th day of May, 1925.

80
